UNITED STATES PATENT OFFICE

HUDSON DONPHIAN RICE, JR., AND JAMES MADISON BABB, OF DALLAS, TEXAS

DUPLEX DISK VALVE

Application filed September 4, 1931. Serial No. 561,278.

This invention relates to an improved valve which is especially adapted for use in a rotary type engine.

The purpose of the invention is to provide 5 a dual sectional valve designed to promote more expeditious operation, whereby to permit opening and closing of the port in approximately one half of the time required by the single disk type valve now employed in 10 engines of the rotary type.

The specific elements selected for accomplishing the desired results will become more readily apparent from the following description and drawings.

15 In the drawings:

Figure 1 is an elevational view of the preferred embodiment of the invention.

Figure 2 is a plan view thereof with the pitman removed to disclose otherwise obscured parts.

Figure 3 is an edge or side elevational view showing the operative position of the novel valve in the motor.

Figure 4 is an ensemble sectional view 25 showing the companion disks forming the novel duplex valve.

Figure 5 is a fragmentary elevational view disclosing a slightly different type of pitman or tappet rod.

30 In carrying the invention into actual practice, I provide a pair of duplicate companion disks 6 and 7, these being provided with eccentric marginal apertures 8 and 9 adapted for registry with each other when the valve 35 is open as seen in Figure 1. There is a concentric stem 10 carried by the disk 7 and extending through and beyond a tubular stem 11 on the disk 7. I provide two different forms of actuating devices. The device 40 shown in Figures 1 to 3 inclusive may be designated as a pitman and it comprises a rod 12 mounted for reciprocatory action and provided with a head 13 carrying an open-ended elongated box-like portion 14. This portion 14 forms a guide and acts to accommodate the anti-frictional rollers 15. I provide a pair of cam rollers for each of the actuating arms 16 and 17. These arms are suitably offset and shaped as indicated in Figure 2 so as to dispose the longitudinally spaced

pairs of rollers in proper longitudinal alignment. The arms are provided at their inner ends with collars 18 and 19, collar 18 surrounding and being fastened to the tubular stem 11 and the collar 19 being keyed to the solid stem 10. The arms are also provided with complementary lugs 20 and 21 spaced apart to accommodate an expansion coil spring 22 which is attached thereto. This spring constitutes a return means and resists 55 the outward spreading of the arms 16 and 17 when downward pressure is brought to bear on the push rod 12. Incidentally when the parts are in the position illustrated in Figure 1, the apertures 8 and 9 of the disks 6 and 7 register to provide an open port. When, however, an upward thrust is brought to bear on the pitman rod 12 this operates the disks 6 and 7 in opposite directions to produce the desired relative oscillatory action, and it requires but a slight oscillatory action to cause the disks to rotate sufficiently to close the apertures 8 and 9 as is obvious.

If, instead of using the pitman arrangement just described, the desired sensitivity of operation or the quick opening and closing of the valve is not acquired, we suggest the use of one of the type illustrated in Figure 5. Here the rod is denoted by the numeral 23, this being formed with an integral segmental head 24 formed with a pair of downwardly converging cam slots 25 and 26 adapted to receive the rollers 15 whereby to provide the desired guide and track action. The gist of the inventive conception, it will be observed, is in the provision of a dual or double-acting valve embodying a pair of companion disks disposed in contact with each other and concentrically connected together for opposite oscillating action, these valves being formed with marginal apertures which are normally registered with each other when the valve is open, and brought out of alignment or registry when the valve is closed. This disk arrangement together with the reciprocatory pitman and the operating connection therebetween together with the spring returning means constitutes the principal fundamental novelty of the structural arrangement.

It is thought that persons skilled in the art 100

to which the invention relates will be able to obtain a clear understanding of the invention after considering the description in connection with the drawings. Therefore, a more ⁵ lengthy description is regarded as unnecessary.

Minor changes in shape, size, and rearrangement of details coming within the field of invention claimed may be resorted to in ¹⁰ actual practice, if desired.

What is claimed is:

1. In a valve and operating structure of the class described, a pair of duplicate rotatable disks disposed in contact with each ¹⁵ other, said disks having registrable marginal apertures, one disk being provided with an outstanding concentric solid stem, the other disk being provided with an outstanding concentric tubular stem, said solid stem ²⁰ extending through and beyond the tubular stem, a pair of operating arms, said arms being provided at their inner ends with collars, one collar being rigidly attached to the solid stem, and the other collar rigidly attached to the tubular stem, spring means ²⁵ associated with the collar equipped ends of said arms for urging the arms in one direction, the opposite ends of said arms being provided with cam and anti-friction rollers, ³⁰ and a reciprocatory pitman rod for moving said arms in the opposite direction against the action of said spring means having guide means with which said rollers cooperate.

2. In a valve and operating structure of the class described, a pair of duplicate disks rotatably disposed in contact with each other, said disks having registrable marginal apertures, one disk being provided with an outstanding concentric solid stem, the other disk ⁴⁰ being provided with an outstanding concentric tubular stem, said solid stem extending through and beyond the tubular stem, a pair of operating arms, and said arms being provided at their inner ends with collars, one ⁴⁵ collar being rigidly attached to the tubular stem, spring means associated with the collar equipped ends of said arms for urging said arms in one direction, the opposite ends of said arms being provided with cam and anti-friction rollers, and a reciprocatory pitman rod for moving said arms in the opposite direction against the action of said spring means having guide means with which said rollers cooperate, said guide means comprising ⁵⁰ an elongated open-ended hollow box-like member having guide tracks with which said rollers have slideable contact.

3. In a valve and operating structure of the class described, a pair of duplicate rotatable disks disposed in contact with each other, said disks having registrable marginal apertures, one disk being provided with an outstanding concentric solid stem, the other disk being provided with an outstanding ⁵⁵ concentric tubular stem, said solid stem ex-

tending through and beyond the tubular stem, a pair of operating arms, and said arms being provided at their inner ends with collars, one collar being rigidly attached to the solid stem, and the other collar rigidly attached to the tubular stem, spring means ⁷⁰ associated with the collar equipped ends of said arms for urging said arms in one direction, the opposite ends of said arms being provided with cam and anti-friction rollers, and a reciprocatory pitman rod for moving said arms in the opposite direction against the action of said spring means having guide means with which said rollers cooperate, said guide means comprising a segmental head ⁷⁵ having a pair of downwardly and inwardly extending elongated guide slots converging toward each other with which said rollers cooperate.

In testimony whereof we affix our signatures.
